[57] CLAIM

The ornamental design for a nose tube anchoring strip, as shown and described.

DESCRIPTION

FIG. 1 is a top plan view of a nose tube anchoring strip, showing my new design;

FIG. 2 is a bottom plan view thereof;

FIG. 3 is a side elevational view thereof, the opposite side being identical thereto;

FIG. 4 is an end elevational view thereof; and

FIG. 5 is an end elevational view thereof, opposite that shown in FIG. 4.

FIG. 1

FIG. 2

FIG. 4

FIG. 3

FIG. 5
